[57] CLAIM

The ornamental design for an aerodynamic fairing for use atop a truck cab and the like, as shown and described.

DESCRIPTION

FIG. 1 is a front perspective view of an aerodynamic fairing for use atop a truck cab and the like showing our new design, it being understood that the broken lines are for illustrative purposes only;

FIG. 2 is an enlarged rear perspective view thereof;

FIG. 3 is a right side elevational view thereof;

FIG. 4 is a front elevational view thereof;

FIG. 5 is a top plan view thereof;

FIG. 6 is a rear elevational view thereof;

FIG. 7 is a bottom plan view thereof; and

FIG. 8 is a sectional view thereof, taken along line 8—8 of FIG. 4.

FIG. 8

FIG. 7

FIG. 6
